US0D1084667S

(12) **United States Design Patent** (10) **Patent No.:** **US D1,084,667 S**
(45) **Date of Patent:** **** Jul. 22, 2025**

(54) **LID OF PACKAGING BOX FOR STORAGE**

(71) Applicant: **L&F PLASTICS, CO., LTD.**, Miaoli County (TW)

(72) Inventor: **Mu-Chuan Hsu**, Miaoli County (TW)

(73) Assignee: **L&F Plastics, Co., Ltd.**, Miaoli County (TW)

(**) Term: **15 Years**

(21) Appl. No.: **29/809,409**

(22) Filed: **Sep. 28, 2021**

(30) **Foreign Application Priority Data**

Mar. 31, 2021 (TW) 110301588

(57) **CLAIM**

The ornamental design for a lid of packaging box for storage, as shown and described.

DESCRIPTION

FIG. 1 is a top front perspective view of a lid of packaging box for storage showing my new design;

FIG. 2 is a front view thereof;

FIG. 3 is a rear view thereof;

FIG. 4 is a right side view thereof and the left side view being a mirror image;

FIG. 5 is a top view thereof;

FIG. 6 is a bottom view thereof;

FIG. 7 is an enlarged cross-sectional view taken along the line 7-7 in FIG. 5; and,

FIG. 8 is a bottom rear perspective view thereof.

The shade lines in the figures show contour and not surface ornamentation.

1 Claim, 6 Drawing Sheets
